DESIGN FOR A STENCIL LETTERING CARD

Ruth Hormats, Baltimore, Md.

Application September 17, 1940, Serial No. 95,149

Term of patent 7 years

To all whom it may concern:

Be it known that I, Ruth Hormats, a citizen of the United States, residing at Baltimore, in the county of Baltimore City and State of Maryland, have invented a new, original, and ornamental Design for Stencil Lettering Cards, of which the following is a specification, reference being had to the accompanying drawing, forming part thereof.

The figure is a plan view of my stencil lettering card showing my new design.

My design for a stencil lettering card is characterized by letters of the alphabet, figures and numerals in their relative positions to the series of circles on the card, together with the measuring ruler placed on one side of the card.

I claim:

The ornamental design for a stencil lettering card, substantially as shown.

RUTH HORMATS.
